(57) **CLAIM**

The ornamental design for a display screen with a dashboard for a user interface, as shown and described.

DESCRIPTION

FIG. 1 is a front view of a first embodiment of a display screen with a dashboard for a user interface;

FIG. 2 is a front view of a second embodiment thereof; and, FIG. 3 is a front view of a third embodiment thereof.

The broken line showing of a display screen in all views are for the purpose of illustrating environment and forms no part of the claimed design. The broken line drawings of a user interface in all views are for illustrative purposes only and form no part of the claimed design.

1 Claim, 3 Drawing Sheets
